UNITED STATES PATENT OFFICE

FREDERICK HENRY WAGNER, OF BALTIMORE, MARYLAND, ASSIGNOR TO THE BARTLETT HAYWARD COMPANY, OF BALTIMORE, MARYLAND, A CORPORATION OF MARYLAND

GAS WASHER

Application filed June 28, 1927. Serial No. 202,124.

This invention pertains to liquid and gas contact apparatus and more specifically relates to a washer in which gases such as blast furnace gases may be washed to remove the solids from the gas.

The invention is illustrated in the accompanying drawings wherein,

Figure 1 is a vertical sectional view of the apparatus;

Figure 2 a transverse horizontal sectional view taken on the line II—II of Figure 1; and

Figure 3 a similar view taken on the line III—III of Figure 1.

15 The main object of the invention is to provide an apparatus wherein the gas is compelled to pass through various sprays; through various water curtains; through various wetted screens; and through sheets 20 of water which are thrown outwardly from the center of the machine toward the inner face of the casing. The arrangement is such that the gases which are forced or drawn through the apparatus take a tortuous passage and, as above noted, pass through the water employed for cooling and cleaning the same.

It will be appreciated that the apparatus may be made of any desired height by employing separate sections or building the casing of the requisite height but in the instant case I have shown, merely for the purpose of illustration, a single casing or shell denoted by 1 and which is cylindrical in form. The 30 shell or casing will be supported upon a suitable foundation, not shown, and is provided with a gas inlet 2 which opens into the lower end of the casing and with a gas outlet 3 at the upper end. Said outlet is in communication with a chamber 4 formed between the top of the casing 5, an annular frusto-conical partition or element 6, and a vertically disposed cylindrical member 7 having an opening 8 in that side thereof remote from the outlet 3. The cylindrical member 7 is open at its lower end and is in direct communication with a chamber 9 immediately below the partition or wall 6.

Extending vertically through the shell is a 40 centrally disposed shaft 10 to which rotary

motion is imparted through any suitable means, not shown. Proper supports for the upper and lower ends of the shaft will, of course, be provided but as these are well known in the art I have not deemed it necessary to illustrate the same.

55 The inlet 2 opens into what may be termed the lower chamber 11, the upper portion of the chamber being defined by the bottom of a pan-like member 12, the upper edge whereof is serrated or notched as shown in Figure 1. This pan will be supported in spaced relation to the walls of the casing by brackets 13 or in any other approved manner.

An outlet pipe 14 is provided in the base 60 of the casing, extending up into the chamber 11 so as to maintain a volume of water within the lower portion thereof. Secured to the shaft 10, or at least that portion thereof which is in the chamber 11, is a pumping element or cone-set 15, said element being the type shown in Letters Patent to Feld No. 983,087, dated January 31st, 1911, though of course any other form of pumping and spraying element may be utilized in so far as the 65 broad invention is concerned. The lower end of this element dips into the water in the lower portion of the apparatus and through centrifugal action tends to draw the water up and spray the same laterally into intimate 70 contact with the incoming gas.

75 Secured to the shaft immediately above the pan 12 is another pumping element or cone-set denoted by 16 and extending outwardly therefrom below the perforated portion is a 80 series of vanes 17 placed in such angular relation as to act as a pump or fan upon the gas and to throw the same outwardly between a series of perforated plates 18 preferably set in an angular relation to each other, as best 85 shown in Figure 2. In other words, the plates, as will be seen upon reference to said figure, are not diametrically arranged within the shell or casing but are thrown off-center so that their ends stand in spaced relation to 90 each other and form passages or pockets into and through which the gas is forced.

95 Overlying and rotatable with the cone-set 16 is a distributor or spray plate 19. This plate is imperforate and extends outwardly 100

to, or slightly beyond, the inner ends of the plates 18 and beyond the edge of this plate 19, and overlying the upper edges of the plates 18, I provide a foraminous surface 20. 5 This surface may be produced from wire screening of the desired and proper mesh.

As will be seen upon reference to Figure 1, the inner portions of the lower edges of the perforate plates 18 are given a downward 10 inclination and a closure plate 21 conforming to such contour is secured in position with reference to such edges. Thus it will be seen that any gas passing upwardly around the pan 12 is caused to travel inwardly toward the center of the washer and then laterally into and between the friction plates 18 and up through the foraminous or screen surface 20. In other words, the plate 19 which overlies the cone-set prevents the gas from 15 passing in a direct upward direction to the next chamber above.

The chamber in which the cone-set 16 operates is denoted by 11^a and the gas, after it passes from said chamber and through the 20 foraminous plate, enters another chamber 11^b. Mounted within this chamber is a pan 22, said pan being supported with its edge in spaced relation to the wall of the casing upon suitable brackets or supports 13^a. The pan, 25 in this instance, is provided with a series of overflow or weir tubes 23, the lower ends of which extend below the bottom of the pan and are notched so as to cause the water to break up in streams as it flows from said 30 pipes. These pipes or weirs maintain a given level of water within the pan so that the cone-set 16^a which cooperates with said pan will always have an adequate supply of water. The arrangement of the friction plates; the 35 foraminous screen; the distributing plate; and the fan blades is the same as that heretofore described and the parts are denoted by the same reference numerals with the exponent "a" added thereto.

40 Above the chamber and elements just described is a further chamber 11^c and in this chamber, as just noted, the same arrangement obtains as to the mechanism and parts as is present in the chamber 11^b.

45 Partitions 22^b will preferably be provided in all of the pans to prevent swirling of the liquid therein.

The wash water is introduced into the apparatus through a pipe 24 connected with any 50 suitable source of supply under pressure, said pipe being connected at its inner end to a head or nozzle 25. As will be seen upon reference to Figure 1, this nozzle is located centrally of the apparatus in fact surrounds the shaft 55 10 and the water discharges from the lower end thereof directly onto the distributor plate 19^a. Inasmuch as said plate is rotated under relatively high speed the water is immediately thrown outwardly in a more or less fine or sprayed condition toward the wall of

the apparatus and over the foraminous screen 20^a. The water then takes the course indicated in the drawings, that is to say it passes inwardly between the plates 18^a, over the closure plate 21^a and into the underlying pan 22^a in a curtain, or screen, or a series of subdivided streams, passing outwardly between the inner ends of the plates 18^a. Here a certain portion of it is repumped by the cone elements 16^b cooperating with the pan 22^a while the excess flows downwardly onto the next underlying distributor plate through the weir tubes or channels 23^a. This flow of the water continues throughout the apparatus until it reaches the pan 12. It flows from this pan through the notches formed in the edge thereof in a series of streams and collects in the bottom of the chamber 11 as indicated in Figure 1.

50 The flow of the gas is indicated by the arrows. Coming into the chamber 11 from the inlet 2 the gas is brought into intimate contact with the liquid which is pumped up and sprayed outwardly by the cone-set 15. It then passes around the pan 12 in intimate contact with the streams of water falling from said pan. It is then deflected inwardly to a certain extent by the closure element 21 and through the down-coming curtain of subdivided streams passing downwardly between the plates 18. Then in its passage it re-curves 55 outwardly, being forced between the inner ends of the plates 18 or into the pocket formed therebetween by the blades 17 through the openings in the plates and upwardly through the foraminous member 20 where it meets the down-coming water passing from the chamber next above. In passing through the pockets formed between the plates 18 the gas is brought into frictional contact with the plates 18 and inasmuch as said surfaces are wetted they tend to remove the solids from the gas through frictional action. So too, as the gas passes upwardly through the screen 20 further frictional action inheres.

60 As the gas leaves the screen or foraminous surface 20, after passing therethrough, it must of necessity pass through the spray or film of water thrown outwardly by the distributor plate 19. Hence at this point the gas is again brought into intimate contact with the water.

65 The flow of gas just set forth inheres in each of the succeeding chambers as the gas passes upwardly until it enters the chamber 4 and passes outwardly therefrom in a clean condition through the outlet 3.

70 It is, of course, to be understood that the pockets formed by the plates 18 (or 18^a) form in effect baffles for the up-going gas. Other types of baffles might be employed in conjunction with the distributor plate and still perform its function of throwing a spray transversely of the up-coming gas. So too, 75 the air propelling means associated with the

pumping elements might be omitted, provided sufficient head is had upon the gas to carry it through the apparatus. The invention is not, therefore, limited to the exact detail and arrangement shown but is to be construed in light of the appended claims.

What is claimed is:

1. In a gas washer, the combination of a casing having a gas inlet and a gas outlet; a liquid pumping and spraying element located within the casing; a series of plates extending inwardly from the wall of the casing forming a series of pockets open at their inner ends; a foraminous surface in the upper portion of the pockets and through which the gas passes; and means for supplying a wash liquid to the pumping and spraying element.

2. In a gas washer, the combination of a casing having a gas inlet and outlet; a liquid pumping and spraying element located within the casing; and a series of plates arranged within the casing, said plates extending inwardly from the inner wall of said casing and forming a series of pockets, said pockets having their inner ends opening toward the pumping and spraying element, the walls of the pockets being angularly arranged with reference to each other.

3. In a gas washer, the combination of a casing having a gas inlet and outlet; a liquid pumping and spraying element located within the casing; and a series of plates arranged within the casing forming a series of pockets, said pockets being closed at their outer end and having their inner ends opening toward the pumping and spraying element, the walls of the pockets being angularly arranged with reference to each other, said walls being perforate.

4. In a gas washer, the combination of a casing having a gas inlet and outlet; a liquid pumping and spraying element located within the casing; a series of plates arranged within the casing forming a series of pockets, said pockets being closed at their outer ends and having their inner ends opening toward the pumping and spraying element, the walls of the pockets being angularly arranged with reference to each other, said walls being perforate; and a foraminous outlet for the pockets located at the upper portion thereof.

5. In a gas washer, the combination of a casing; a combined liquid pumping and spraying element located centrally thereof; a series of plates located around the same forming a series of pockets, the inner ends of said pockets opening toward the spraying element; and means associated with the latter element for forcing the gas into the pockets.

6. In a gas washer, the combination of a casing; a liquid pumping and spraying element mounted therein; means arranged in line with the spray for baffling the passage of a gas through the washer;

means associated with the pumping and spraying element for throwing liquid transversely of the flow of gas from the baffling means; and means for feeding liquid to said liquid throwing means.

7. In a gas washer, the combination of a casing; a liquid pumping and spraying element mounted therein; means arranged in line with the spray for baffling the passage of gas through the washer; an imperforate plate overlying the pumping and spraying element and rotatable therewith, said plate lying in a plane substantially coincident with the gas discharge of the baffle means; and means for feeding liquid to said plate.

8. In a gas washer, the combination of a casing; a liquid pumping and spraying element mounted therein; a plurality of plates extending inwardly from the wall of the casing toward said pumping element, said plates being perforate and standing at an angular relation to each other and forming a series of pockets opening toward the pumping and spraying element; a closure extending around beneath the lower edges of said plates; an annular screen surface overlying the outer upper edges of said plates and forming a gas discharge from the pockets; a distributor plate associated with the spraying and pumping element; and means for feeding liquid to said plate.

9. In a gas washer, the combination of a casing having a gas inlet at its lower end and a gas outlet at its upper end; means for introducing liquid into the upper portion of the casing and centrally thereof; a shaft extending down through the casing; a pan standing in spaced relation to the walls of the casing; an inverted frusto-conical pumping and spraying element carried by the shaft and dipping at its lower end into the pan; a distributor plate overlying the upper end of said frusto-conical element and upon which the liquid introduced into the washer is discharged; a series of plates extending inwardly from the wall of the casing, and forming a series of pockets opening at their inner ends in line with the spray forming portion of the frusto-conical element; and a foraminous body overlying the upper portion of the pockets adjacent their outer ends.

10. In a gas washer, the combination of a casing having a gas inlet at its lower end and a gas outlet at its upper end; means for introducing liquid into the upper portion of 120 the casing and centrally thereof; a shaft extending down through the casing; a pan standing in spaced relation to the walls of the casing; an inverted frusto-conical pumping and spraying element carried by the shaft 125 and dipping at its lower end into the pan; a distributor plate overlying the upper end of said frusto-conical member and upon which the liquid introduced into the washer is discharged; a series of plates extending inward- 130

ly from the wall of the casing and forming a series of pockets, said pockets having openings at their inner ends in line with the spray forming portion of the frusto-conical element; a foraminous body overlying the upper portion of the pockets adjacent their outer ends; and means associated with the frusto-conical member for forcing the gas into the open ends of the pockets.

10 11. In a gas washer, the combination of a casing having a gas inlet at its lower end and a gas outlet at its upper end; means for introducing liquid into the upper portion of the casing and centrally thereof; a 15 shaft extending down through the casing; a series of pans mounted in the casing in spaced relation to each other and to the walls of the casing, a plurality of successive pans having at least one weir which discharges water in 20 a downward direction inward of the marginal portion of the pan; a pumping and spraying element mounted above each pan and secured to the shaft for rotation therewith, the lower end of each pumping element extending 25 into the pan immediately below the same; a series of perforate partitions forming pockets extending inwardly from the inner wall of the casing in line with each of the spraying elements, said pockets being open at their 30 inner ends; an annular foraminous body overlying the upper outer ends of said pockets to form gas discharge openings; and a distributor plate associated with each of the pumping and spraying elements, said distributor 35 plate serving to throw outwardly the liquids which is discharged thereon.

12. In a gas washer, the combination of a casing having a gas inlet at its lower end and a gas outlet at its upper end; means 40 for introducing liquid into the upper portion of the casing and centrally thereof; a shaft extending down through the casing; a series of pans mounted in the casing in spaced relation to each other and to the walls of the 45 casing, a plurality of successive pans having at least one weir which discharges water in a downward direction inward of the marginal portion of the pan; a pumping and spraying element mounted above each pan and secured to the shaft for rotation therewith, the lower end of each pumping element extending 50 into the pan immediately below the same; a series of perforate partitions forming pockets extending inwardly from the 55 inner wall of the casing in line with each of the spraying elements, said pockets being open at their inner ends; an annular foraminous body overlying the upper outer ends of said pockets to form gas discharge openings; 60 a distributor plate associated with each of the pumping and spraying elements, said distributor plate serving to throw outwardly the liquid which is discharged thereon; and a series of radially disposed inclined blades 65 extending outwardly from each of the pump-

ing and spraying elements and acting to force the gas inwardly into the pockets.

In testimony whereof I have signed my name to this specification.

FREDERICK HENRY WAGNER.
